Des. 222,872
Patented Jan. 25, 1972

222,872

SPANNER

Guy Boucher, Paris, France, assignor to E.F.E. (European Fund Establishment), Vaduz, Liechtenstein

Filed June 10, 1970, Ser. No. 23,426

Claims priority, application France Dec. 26, 1969

Term of patent 14 years

Int. Cl. D8—05

U.S. Cl. D8—22

FIG. 1.

FIG. 2.

FIG. 3.

FIG. 4.

FIG. 1 is a side elevational view of a spanner, the opposite side being reversely similar;

FIG. 2 is an end view of the right side of FIG. 1;

FIG. 3 is a top view of the spanner of FIG. 1; and FIG. 4 is a bottom view of the spanner of FIG. 1.

I claim:

The ornamental design of a spanner, as shown and described.
